SAFETY STOP FOR CUTTER CHAINS

Clarence Horner, Windber, Pa.

Application July 6, 1936, Serial No. 89,198

4 Claims. (Cl. 262—33)

This invention relates generally to mining machines and in particular to a safety device for preventing accidents due to the operation of a cutter chain of a mining machine, while the same is being moved from place to place. The invention will be fully apparent from the following detailed description when read in connection with the accompanying drawing, in which

Fig. 1 is a plan view diagrammatically illustrating a mining machine, the cutter arm of which is equipped with an improved safety device; Fig. 2 is an enlarged plan view of the cutter arm with the safety device in position; Fig. 3 is a horizontal section on line 3—3 of Fig. 2; Fig. 4 is an enlarged section on line 4—4 of Fig. 3; Figs. 5 and 6 are detail views of the safety device detached from the cutter arm.

Referring in detail to the drawing, 10 is a diagrammatic representation of a mining machine, which may be regarded as of conventional form. 11 is a motor mounted thereon, which is connected by means of a worm 12 and gearing 13 and a clutch 13^a to an upright shaft 14 carrying a sprocket wheel 15 adapted to propel a cutter chain 16, which carries a plurality of cutter bits 17. These cutter bits are mounted in special links 18, which are joined by connecting links 19. The cutter chain is guided in ways formed by plates 20 and 21 secured to the cutter arm 22. The cutter arm as a whole is adapted to be swung about the axis of the upright shaft 14, so as to cut a kerf under a seam of coal or the like.

The particular feature of the present invention relates to a safety stop, which is adapted to be detachably secured to the cutter arm, so as to prevent the cutter chain from moving in either direction when the machine is not in use or when the machine is being propelled from one location to another, if for any reason the customary clutch controlling the drive should become engaged either through failure of the mechanism or a mistake on the part of the operator.

The safety device comprises a bar-like member 23 having a downwardly extending portion 24, the extremity of which is bent inwardly to form a tooth 25 adapted to enter the space between two adjacent links of a cutter chain. The member 23 is detachably secured to the cutter bar by means of a removable pin 26 having a perforated handle 27 formed thereon. The pin 26 passes through an opening 28 in the member 23 and engages registering openings 29 and 30 in the plates 20 and 21.

As thus arranged, it is clear that when the member 23 is placed in position, as indicated in the drawing that the tooth 25 thereof will serve to prevent motion of the cutter chain, even though the control clutch should be inadvertently thrown while the motor is in operation. A safety feature of this kind is particularly desirable for mining machines which are frequently used underground, where the illumination is poor and where the mechanism is frequently operated by relatively unskilled labor of a low order of intelligence.

While I have described quite specifically the particular embodiment of the invention herein illustrated it is to be understood that I am not limited thereto since various modifications may be made within the scope of the appended claims.

What I claim is:

1. In combination, a mining machine having a cutter arm, a cutter chain guided thereby, driving mechanism for the cutter chain, and a perforated safety stop bar having a detachable pin connection with the cutter arm and provided with an abutment to project between the cutter links of the chain.

2. In combination with a mining machine having a cutter arm carrying a power driven cutter chain, a safety device comprising a perforated member detachably secured by a removable pin to said cutter arm, said member having a portion adapted to be positioned between the cutter bit links of the chain so as to prevent movement thereof.

3. In combination with a mining machine having a cutter arm and a power driven cutter chain guided thereby of a safety device comprising a bar connected by a removable pin with a cutter arm, said bar having a tooth portion adapted to be positioned between adjacent links of the chain so as to prevent movement thereof.

4. In combination with a mining machine having a pivotally mounted cutter arm, a cutter chain guided thereby, power driving means including a clutch for transmitting power to said chain through the pivotal axis of said cutter arm and a safety device comprising a bar connected by a removable pin with said cutter arm and having an abutment projecting into the path of the cutter links and effective to prevent the movement of the cutter chain when said clutch is accidentally engaged.

CLARENCE HORNER.
